UNITED STATES PATENT OFFICE

PHILIP J. BURKLE, OF ELKHART, INDIANA, ASSIGNOR TO C. G. CONN, LTD., OF ELKHART, INDIANA, A CORPORATION OF INDIANA

WIND MUSICAL INSTRUMENT

Application filed September 18, 1930. Serial No. 482,735.

This invention relates to improvements in musical instruments normally keyed to a single tone, as for instance to bugles.

It is an object of the invention to provide 5 an instrument of this type facilities for changing readily from one tone to another, so as to alter, for instance, a tone to which a bugle is keyed, selectively from G to D or vice versa.

10 It is also an object of the invention to provide an instrument of this type in which the alteration from one tone to another may be effected without material alteration of the appearance of the instrument.

15 It is another object of the invention to provide in an instrument of this type selective different paths for the sound, and to maintain one of said paths inactive or closed to the advance of the sound when the instrument is set to its normal key, an additional path or by-pass for the propagation of the sound being freed at the time when the normal path of the tone is closed to the propagation thereof.

20 25 It is an additional object of the invention to provide an instrument of this type with a by-pass of relatively great length selectively insertable into the path of the sound, whereby through the additional length through which 30 the sound has to travel the key thereof is altered.

It is furthermore an object of the invention to provide in a bugle of the character described a plurality of rigidly interconnected 35 similarly operable valves adjustable to permit the passage of the sound in either one of two predetermined ways.

With these and numerous other objects in view an embodiment of the invention is illustrated in the accompanying drawings to which reference is made in the following specification.

In the drawings:

Figure 1 is a side elevation of an improved 40 bugle of this character.

Figure 2 is a side elevation of the same instrument viewed from the opposite side.

Figure 3 is an enlarged detailed sectional 45 view of the valve structure in normal position.

Figure 4 is an end elevation of said valve structure.

Figure 5 is partly side elevation and partly 55 section of the valve structure and pertaining portions of the instrument.

Figure 6 is a fragmentary side elevation and detailed sectional view similar to Figure 5 showing the valve structure in adjusted position, and

Figure 7 is a horizontal sectional view on 60 line 7-7 of Figure 6.

The instrument comprises a sound tubing made up of straight portions which are interconnected by bent portions to form one continuous path for the sound produced by the application of the mouth of the player to the mouth piece 1. The straight portion 2 of the tubing connected with the mouth piece merges into the bend 3 to communicate with a parallel straight portion 4, the bend 5 whereof establishes communication with another straight tube portion 6 having a sharper bend 7 in which the improved valve assembly 8 is inserted and this bend 7 which establishes communication with another straight portion 9 leads through the gradually enlarged path 10 to the sound outlet or bell 11.

The valve assembly which is inserted in 70 the bend 7 is primarily illustrated in Figures 3 to 7 inclusive and comprises a stationary casing in the form of a straight tube 13 from which at fixed distances short tubular extensions or nipples 14 and 15 project at right 75 angle to the tube 13 in opposite directions parallel to each other. The straight portion 13 is provided, in axial alignment with the nipples 14 and 15, with transverse openings 16 and 17 respectively.

The nipples 14 and 15 maintain in axial alignment with said openings 16 and 17 the tubes 18 and 19 respectively which are firmly 80 united with the straight casing 13 so as to constitute together with the tube 13 and the short nipples 14 and 15 a rigid self-contained structure adapted to be positioned between the straight portions 6 and 9 of the tubing.

Each of the fixed tubes 18, 19 contains a short slideable tube 20, 21 respectively intersecting the tube 13. Each of these short 85 90 95 100

slidable tubes 20, 21 is provided with a transverse short tube 22, 23 respectively adapted to be normally maintained in alignment with the fixed tube 13. The slidable tubings 20, 21, however, are extended beyond their intersection with the straight tube 13 and are provided each with a closure wall 24, 25 respectively extending transversely over the entire cross section of the pertaining tube 20, 21.

10 Beyond this closure the tubes 20, 21 are each provided with a circular opening, one opening 26 having its center in the uppermost line of contour of the tube 20 and the other opening 27 having its center in the lowermost line 15 of contour of the tubing 21.

It is obvious, therefore, that upon the tubes 20, 21 being positioned as indicated in Figures 3 or 5 a direct sound passage is provided through the sound tubing as shown by 20 the arrows and no communication is established between this tube 13 and the tubes 20, 21.

If, however, both of these tubes 20 and 21 are shifted to the left (Figure 3) to assume 25 the position shown in Figure 7 the cross walls of the tubings 20, 21 and the closure walls 24, 25 will obstruct the propagation of the sound towards the left but will provide a different path since the openings 26 and 27 30 are now in alignment with the tube 13.

For the purpose of facilitating the simultaneous adjustment of the valve tubes 20 and 21 to provide either a straight passage 30, Figures 3 and 5, or to obstruct this straight 35 passage, there is provided a connecting bend 28 secured by a nipple 29, 30, Figures 6 and 7, to said slidable tubes 20 and 21, and disposed to facilitate the gripping of the two tubes for the purpose of adjustment.

40 When, therefore, the direct passage through the tubing 13 is obstructed upon movement of the two valve tubes 20, 21 to the left this tube 13 is in communication with a by-pass 31 of relatively great length, as shown in Figures 2 and 5. This by-pass comprises the two straight portions 32 and 33 and the bend 34. The straight portions are both 45 parallel to each other and connected each at one end with the bend 34 while the opposite 50 ends are associated through O-G tubes 35 and 36 respectively and through a nipple 37 and 38 with the horizontal rigid tubes 18 and 19 of the valve assembly 8.

55 It will be obvious from the above that upon the movable valve structure 20, 21, 28 assuming the position shown in Figures 3 and 5 the sound will travel through the straight portion of the tube and then continue in a direct path to the discharge of bell 6 of the instrument. When the movable valves have 60 been adjusted to the position shown in Figures 2, 6 and 7 respectively, however, the straight path through the tubing 13 is obstructed and the sound is by-passed through 65 the tube 31, as indicated by the arrows, Fig-

ure 7, over a relatively long path which will naturally alter the pitch or key of the tone.

Hence by means of a slight adjustment of a valve structure the key of the entire instrument may be varied. While the normal key 70 may be G, the key to which the instrument may be altered will then be D and in a very simple way the restoration to the original key G may be effected.

For the purpose of determining the proper 75 position of the valve structure upon alteration of the instrument means are provided for limiting the shifting movement of the movable valves in either direction. A lug 40 is secured to the stationary tube 14 adjacent 80 the end thereof. A similar lug structure 41 is fixedly mounted on one of the shiftable tubes as 20, this lug 41 for instance being secured as shown in Figures 5 to 7 on the nipple 29 through which the bend 28 is connected 85 with both of the tubes 20 or 21.

A pin 43 extends through the two lugs 40 and 41 and may be secured fixedly as by soldering or in some other suitable way to the 90 movable lug 41. This pin is provided at the opposite end where it projects from the lug 40 with a head 44 which may be adjustable thereon and it is obvious, therefore, that the maximum extension obtainable is determined by the variable effective length of the pin 43. 95 The maximum inward extension also is limited, as indicated in Figure 5, by that position in which the nipple 29 abuts the outer end of the stationary tubing 14.

From the above it will be seen that the 100 alteration of the instrument from one key to another can easily be accomplished at any desired instant through the proper adjustment of the movable valve structure, for utilizing the by-pass 31 to alter the character 105 of the tone, or for shutting off the by-pass from utilization by not only providing the path through the straight tube 13 but also directly obstructing the inlet to the by-pass 33 through the transverse walls 24 and 25 respectively. 110

I claim:

1. In an instrument of the character described, the combination of a sound tubing, a valve assembly forming a part thereof, a pair of fixed guide tubes extending from said valve assembly, a by-pass in open communication with said guide tubes, and valve tubes slidable within said guide tubes, said valve tubes containing means for opening the path through said valve assembly, and means for obstructing a path through said valve assembly and opening a path through said by-pass. 115

2. In an instrument of the character described, the combination of a sound tubing, a valve assembly inserted therein, tubular extensions in said valve assembly, a relatively long by-pass tube mounted on said extensions, valve tubes slidable in said extensions, and means for simultaneously adjusting said 120 125 130

valve tubes to the same extent relatively to the valve assembly.

3. In an instrument of the character described, the combination of a sound tubing, a valve assembly inserted therein, tubular extensions on said valve assembly, a by-pass connected with said extensions, valve tubes slideable in said extensions, and a bend connecting said slideable valve tubes, said valve tubes containing transverse tubings in alignment with the sound tubing when said slideable valve tubes have been shifted to a predetermined position and also containing transverse closure walls adapted to obstruct the sound through said valve tubes when the latter have been shifted to another predetermined position.

4. In an instrument of the character described, the combination of a sound tubing, a valve assembly inserted therein, tubular extensions on said assembly, a by-pass permanently in communication with said extension, valve tubes slideably within said extensions and a bend connecting the portions of the slideable valve tubes which project from said extensions, the valve tubes enclosing transverse tubings in alignment with each other and the sound tubing when the valve tubes have been moved to a predetermined position to provide a straight passage for the sound through said valve assembly and sound tubing, said slideable valve tubes also enclosing a transverse obstruction and being provided with circular openings, whereby upon a different adjustment of said slideable valve tubes said obstruction is in alignment with a wall of the sound tubing and said circular openings are in alignment with the bore of the sound tubing to provide a sound passage through the by-pass and to obstruct the direct sound passage through the sound tubing.

5. In an instrument of the character described, the combination of a sound tubing, a valve assembly inserted therein, tubular extensions on said valve assembly, a by-pass communicating with said tubular extensions, valve tubes slideable in said extensions, and means for connecting said valve tubes, said tubular extensions each containing a transverse tubing held in alignment with each other, and each valve tube also containing a transverse wall and having a circular opening, the circular openings on the two valve tubes being located at diametrically opposite points of said tubes, whereby upon selective adjustment of said valve tubes a straight sound passage through the sound tubing is produced, or said straight sound passage is obstructed and a sound passage through the by-pass is produced.

6. In an instrument of the character described, the combination of a sound tubing, a valve assembly inserted therein, transverse extensions on said valve assembly, a by-pass communicating permanently with said exten-

sions, valve tubes slideable within said extensions, and means in said valve tubes for selectively providing a straight sound passage through the tubing and valve assembly and for providing a by-pass for the sound, respectively.

7. In an instrument of the character described, the combination of a sound tubing, a valve assembly inserted therein, a pair of tubular extensions on said valve assembly, a by-pass in communication with said extensions, slideable valve tubes in said extensions, means for simultaneously adjusting said valve tubes to produce a direct passage through the sound tubing or to close the direct passage and simultaneously produce a sound passage through the by-pass, respectively, and means for determining the extent of adjustment of said valve tubes.

8. In an instrument of the character described, the combination of a sound tubing, a valve assembly inserted therein, tubular extensions on said valve assembly, a by-pass communicating with said tubular extensions, slideable valve tubes within said tubular extensions, means in said valve tubes for selectively establishing a direct sound passage through the sound tubing, a sound passage through said by-pass, respectively, common means for adjusting said valve tubes, and variable means for limiting the extent of said adjustment.
